UNITED STATES PATENT OFFICE.

JEREMIAH F. VOORHEES, OF PHILADELPHIA, PENNSYLVANIA, ASSIGNOR OF ONE-HALF TO NATHANIEL B. K. HOFFMAN, OF NEW YORK, N. Y.

FLUID-PRESSURE BRAKE FOR RAILWAY-TRAINS.

SPECIFICATION forming part of Letters Patent No. 739,761, dated September 22, 1903.

Application filed December 5, 1898. Serial No. 698,388. (No model.)

To all whom it may concern:

Be it known that I, JEREMIAH F. VOORHEES, a citizen of the United States, residing at Philadelphia, in the county of Philadelphia and State of Pennsylvania, have invented a new and useful Improvement in Fluid-Pressure Brakes for Railway-Trains, which improvement is fully set forth in the following specification, reference being had to the accompanying drawings, in which similar characters of reference indicate similar parts.

My invention relates to an independent controlling device for automatic fluid-pressure brakes described in my Patent No. 615,326, bearing date December 6, 1898.

In the present improvement I substitute an improved relief-valve mechanism in connection with the brake-cylinders for that described in said patent, and I add to the locomotive equipment an auxiliary storage-reservoir and an automatic pressure-valve for the purpose of enabling the auxiliary train-pipe forming part of said controlling device to be charged with fluid-pressure without the same being taken directly from the main reservoir when it is not expedient to do so.

The usual connections of an automatic brake apparatus such as now in general use being so well known they are not illustrated.

In the drawings, Figure 1 is a diagrammatic side elevation showing the several parts of my improved controlling device and their connections. Fig. 2 is a plan view of the engineer's valve C in section. Fig. 3 is an enlarged vertical section of the variable relief-valve mechanism F, and Fig. 4 is an enlarged vertical section of the pressure-valve A'.

The valve A' is interposed between the main reservoir (not shown) and an auxiliary storage-reservoir A, which is connected with an auxiliary engineer's valve C through a pipe B and a pressure-reducing valve B', which may be of ordinary construction and adapted to limit an accumulation of pressure in the pipe B, as may be desirable.

The valve C is an ordinary three-way cock connecting the auxiliary train-pipe D with the supply-pipe B or with the atmosphere, an intermediate position of the plug-valve C' blanking all ports. A gage I, situated on the locomotive, enables the engineer to be accu-

rately informed as to the amount of pressure he admits to or releases from the pipe D through the valve C.

The auxiliary train-pipe D extends throughout the train and is connected by a branch pipe D' at each car with a variable relief-valve F for the brake-cylinder H.

It is now common to maintain a greater pressure in the main reservoir than in the main train-pipe of the usual automatic brake apparatus, and this extra pressure can be used for charging the auxiliary train-pipe D without inconvenience, for the fact that the automatic valve A' will prevent the pressure in the main reservoir from being thereby reduced to an extent that would cause a return of fluid-pressure thereto from the main train-pipe, and the pressure stored in the auxiliary reservoir A will insure sufficient pressure in the pipe D when needed. A partition A³ in the valve-casing A' forms a seat for a valve A⁴, which is connected to a piston A⁵ within a cylinder forming part of the valve-casing. A flexible gasket A⁶ is interposed between the piston and a plate A⁷. Its outer edge is secured on an offset by the annular flange of the screw-cap A⁸. A spring A⁹, interposed between the plate A⁷ and a regulating-stud A¹⁰, acts to retain the valve A⁴ on its seat.

The piston A⁵ is subject at all times to the main reservoir-pressure, which acts on the piston in direction to open the valve against the resistance of the spring and allow the fluid-pressure to pass from the main reservoir to the reservoir A, and the regulating-stud enables the resistance of the spring to be adjusted to close the valve when the pressure in the main reservoir does not exceed an amount usually employed in the main train-pipe.

The valve-casing F is divided into separate compartments by an actuating-diaphragm F', the outer edge of which is secured on an offset F² by the annular flange of the screw-cap F³. A plate F⁴ and a cylindrical guide-block F⁵, fitted into the tube F⁶, forming part of the screw-cap F³, are, with the diaphragm, secured on a smaller end of the valve-stem by means of a nut F⁷. Into the lower end of the tube F⁶ is fitted a regulating-stud F⁸, and between it and the guide-block F⁵ is interposed a spring

F⁹. A cap F¹⁰ serves as a lock-nut for the regulating-stud. The interior of the screw-cap is subject to pressure in the auxiliary train-pipe D, to which it is connected by the 5 branch pipe D'. The main body of the valve-casing is open to the atmosphere to an extent that will prevent an appreciable accumulation of pressure therein. A chamber F¹¹ is in constant communication with the brake-cylinder through the pipe E. A valve F¹², which may form part of the stem F¹³ or be separate therefrom, at the option of the constructor, is adapted to form a tight joint with an annular seat F¹⁵ by means of a gasket F¹⁶, 10 secured to the face of the valve by means of a nut engaging with a thread on a larger part of a stem F¹⁴, which is rigidly connected to the valve and extends into a central hole in a perforated bridge F¹⁷, which acts as a guide 15 for it.

From the fact that the space between the relief-valve and the diaphragm F' is open to the atmosphere their relative areas determine a proportionate efficiency of pressure in the 20 auxiliary train-pipe D to retain pressure in the brake-cylinders in excess of an amount retained therein by the action of the relief-valve springs in a manner similar to that described in my prior patent, and the proportion 25 may be at the option of the constructor; but to obtain the best results it should be such that the maximum pressure employed in the pipe D need not exceed an amount just sufficient to admit of graduation.

30 The amount of clearance between the plate F⁴ and the annular end of the tube F⁶ should not exceed one thirty-second of an inch when the valve is seated, thereby preventing the valve from forcibly striking its seat when 35 there is a sudden reduction of pressure in the brake-cylinder, and the opening through the valve-seat F¹⁵ should be proportioned to release pressure from the brake-cylinder H as rapidly as admitted thereto through the triple-valve mechanism and pipe G with this amount 40 of clearance of the valve from its seat.

The relief-valve springs should be uniformly adjusted to retain in the brake-cylinders a pressure that will exert a braking force 45 proportionately less than the weight of the car when stationary.

Limitation in the amount of fluid-pressure stored in the auxiliary reservoirs of the usual car-brake apparatus is unnecessary when my 50 controlling device is employed, for the fact that said stored pressure cannot then become effective as a braking force in excess of an amount determined by the adjustment of the relief-valve springs unless so determined 55 by the engineer from the locomotive of the train and cannot exceed to an appreciable extent the amount so determined. A sufficient pressure should therefore be maintained in the auxiliary reservoirs to apply the brakes 60 with the greatest amount of force that can be advantageously employed at any time and the maximum force with which the brakes 65

can be automatically applied predetermined by the engineer according to the amount of pressure he permits to accumulate in the 70 auxiliary train-pipe D.

The engineer is by means of my controlling device enabled to positively regulate the braking force according to the speed of the 75 train and atmospheric conditions affecting the adhesion of the wheels to the rails. He can also cause a reduction in the amount of pressure in the brake-cylinders when it exceeds a specific amount by releasing the pressure from the auxiliary train-pipe D through 80 the valve C and with great rapidity on account of the small volume of fluid-pressure necessarily released from the auxiliary train-pipe in order to enable the relief-valves to almost instantly reduce the pressure in the 85 brake-cylinders a proportionately greater amount.

The engineer can control a reduction in the force with which the brakes are applied in the manner described whatever may cause the 90 brakes to be applied, excepting the train parting. Should this occur after the auxiliary train-pipe has been charged and quick-acting triple valves are employed, the serial 95 action of the brakes will be more rapid than the entire release of pressure from the auxiliary train-pipe at place of parting, and the pressure therein will for a short length of time act to retain an extra pressure in the 100 brake-cylinders and aid in stopping the train.

In case of the brakes being automatically applied from any cause when there is no pressure in the auxiliary train-pipe the pressure admitted to the brake-cylinders in excess of an amount sufficient to overcome the resistance 105 of the relief-valve springs escapes to the atmosphere through the relief-valves as rapidly as it enters the brake-cylinders. The maximum force with which the brakes can be automatically applied is therefore primarily determined by the resistance of the relief-valve springs and cannot exceed this amount unless the engineer admits pressure to the auxiliary train-pipe to act on the diaphragm and cylindrical guide-block at each 110 relief-valve to increase the load of said valve, 115 this being the general nature of my invention as set forth in my prior patent previously referred to.

The present improvement eliminates the 120 risk of the brakes being automatically applied on account of charging the auxiliary train-pipe while the train is moving and, further, increases the efficiency of pressure in the auxiliary train-pipe without increasing the area 125 of the relief-valve to an undesirable extent. I consider all known substitutes and equivalents as within the scope of my invention.

I claim as my invention and now desire to 130 secure by Letters Patent—

1. In a controlling device for fluid-pressure brakes, the combination of a main storage-reservoir, an auxiliary storage-reservoir, an automatic valve controlling a connection be-

tween said reservoirs, and a pressure-reducing valve for limiting a flow of pressure from said auxiliary storage-reservoir to an auxiliary train-pipe, substantially as specified.

5. 2. A valve-casing containing a relief-valve interposed immediately between a brake-cylinder and the atmosphere, a piston or diaphragm, one side of which is exposed to the atmosphere the opposite side being subject 10 to fluid-pressure in an auxiliary train-pipe, and a stem or rod interposed between said relief-valve and piston or diaphragm, substantially as specified.

3. A valve-casing having a connection to an auxiliary train-pipe and another to a brake-cylinder, and an intermediate compartment open to the atmosphere, a relief-valve opening from a brake-cylinder to said intermediate compartment, a piston or diaphragm interposed between said compartment and an auxiliary train-pipe, a stem or projection connected with said diaphragm or piston, and adapted to engage with said relief-valve, a spring acting in concert with fluid-pressure 25 acting on said piston or diaphragm, to counteract pressure in a brake-cylinder, acting to open the relief-valve, substantially as specified.

4. A valve-casing having a piston or diaphragm fitted therein, one side of which is subject to pressure from a retaining-pipe while the opposite side is exposed at all times to the atmosphere, a stem or projection con-

nected with said piston or diaphragm and adapted to engage with a valve controlling a 35 port opening directly to the atmosphere from the interior of the valve-casing subject to pressure from a brake-cylinder, a seat for the valve situated in such a manner, that fluid-pressure within an opening through the valve- 40 seat acts on the valve in direction to unseat it, the opposite side of the valve being exposed at all times to the atmosphere and the proportion of the area of the valve subject to pressure from the brake-cylinder to that of 45 said diaphragm or piston, subject to pressure from said retaining-pipe, determining the effectiveness of said pressure to retain the valve on its seat substantially as specified.

5. In a fluid-pressure brake apparatus, the 50 combination with the brake-cylinders and a main fluid-pressure supply, of a pressure-retaining valve A', storage-reservoir A, pressure-reducing valve B', supply-pipe B, engineer's valve C, auxiliary train-pipe D, and 55 an automatic variable relief-valve F, adapted to vent excess pressure immediately to the atmosphere, interposed immediately between each brake-cylinder and said auxiliary train-pipe, substantially as specified. 60

Signed by me this 23d day of November, 1898.

J. F. VOORHEES.
